UNITED STATES PATENT OFFICE

GENNARO DE PAMPHILIS, OF NEW YORK, N. Y.

PAD

Application filed June 12, 1929. Serial No. 370,204.

This invention relates to sheet pads in general and to the method of stacking sheets into pads in a certain predetermined manner, and for certain purposes which will be presently evident.

The prime object of my invention is the method of producing a pad by stacking up a plurality of individual, unbound, uniformly sized sheets in such a manner as to facilitate the separation and removal from the stack of the upper sheet or sheets, one or more sheets at a time, without disturbing the remaining sheets.

Another object of my invention is to provide means for accomplishing the primary object sought.

The foregoing and further objects will be more fully apparent from the following description and the accompanying drawings, forming part of my disclosure, but by no means intended to limit it to the actual showing, and in which

Figure 1 is a plan view of a preferred form of my device.

Figure 2 is a longitudinal cross sectional view therethrough, showing the pad sheets in elevation, and

Figure 3 is a front elevation of my device.

Referring to the figures, numeral 10 designates the base or pad support of my pad holder, preferably resting upon a pad 11, which may be made of rubber, felt or other resilient material.

The pad support comprises a platform 35 from which extend upwardly, edge portions adapted to limit the movement of the pad within the holder. At one side of the pad there will be observed an upright edge portion 12, provided with an aperture 13, adapted to receive a cord, chain or spring, not shown in the drawings, connecting a pencil to the pad holder.

At the front of the pad holder an inclined edge portion 14 may be observed which is joined with the edge portion 12. Edge portion 14 is rounded at its upper right hand corner, as can be seen at 15. Opposite edge portion 12 there will be observed a somewhat shorter edge portion 16, indicated in broken lines in Figure 2.

At the rear of edge portions or guards 12 and 16, there are provided extensions 17 in which are cut slots 18, the purpose of which will be explained presently. The rear edge of the device is indicated at 19. This rear edge is inclined similarly to the front edge portion 14 and is provided with a cut-out, indicated at 20.

Placed near the rear end portion 19 and between the rear ends of the edge portions 12 and 16, there will be observed a weight 21, loosely fitting in the holder. Extending from the weight member 21 are screws or rivets, indicated at 22, which project through guide slots 18 of extensions 17. These slots are inclined parallel to the rear and front edge portions and form guides for the weight member 21.

Arranged below the weight member 21 and held within the several edge portions of the pad holder, is a stack of uniformly sized, unbound, loose sheets forming a pad. Due to the arrangement of the rear and front edges, the stack of sheets necessarily assumes the shape of a parallelogrammatic prism. Weight member 21 compresses the sheet stack near the inclined rear edge so as to prevent the sheets from voluntarily leaving the pad holder. Due to the fact that the front edge of the stack of sheets is inclined, it is readily evident that this arrangement facilitates the separation of the topmost sheet or sheets from the rest of the pad.

In order to still further increase the facility of lifting the sheets from the pad holder, and particularly when the stack of sheets has diminished in size, I prefer to round off the right hand corner of the supporting platform 10, as indicated at 22.

In the foregoing description and in the drawings I have dwelled upon the fact that only the front and the rear edge portions are inclined; be it understood, however, that it is readily practical to incline all four edges so as to force the stack of sheets to not only extend towards the front but also towards one or the other side, preferably to the right side so that the corner 23 of the uppermost sheet will not only extend beyond the front edge of the lowermost sheet, but also beyond

the right hand side edge thereof. This arrangement is not shown in the drawing since it is obvious that such arrangement may be readily accomplished, as explained above. It will be obvious that in case the stack of sheets is arranged in this manner, the right hand outer corner of the sheets can be picked up with still greater ease than is possible in the arrangement shown in the drawing.

10 Referring to Figures 1 and 2, the cut-out 20 permits lifting the weight bar 21 when a stack of sheets is placed into the holder.

15 The arrangement and function of my device, as shown in the drawings and as described above, clearly sets forth in which manner a plurality of sheets may be stacked into pad form and held in that form so as to permit the removal of the topmost sheet while the rest of the stack is not affected.

20 It is obvious that the application of this method or principle may find manifold use, one of which is its application as a paper or note pad to be placed upon a desk. It is further obvious that the article may be used 25 for permanent advertising purposes, in that an advertising label or other advertising matter is placed upon the weight bar.

30 It is obvious that the method of forming paper pads, as described above, not only decreases considerably the cost of note pads by 35 eliminating the binding together of the sheets, and by permitting the stacking up of an unlimited quantity of loose sheets, but also by facilitating the keeping of the pad at a uniform thickness by replacing used sheets.

40 While I have shown and explained certain forms, it is evident that changes and variations may be made within the scope of my invention, and I therefore reserve for myself the right to make such changes or improvements without departing from the broad scope thereof.

45 I claim:

45 1. A sheet pad holder, comprising a pad support having upright and inclined pad-limiting means, said upright pad limiting means provided with weight guides, and a weight bar arranged between and having 50 portions slidably mounted within said guides for exerting a pressure in the direction towards said pad support.

55 2. A sheet pad holder, comprising a pad support having a plurality of upturned edge portions forming pad-limiting means, one 60 of said edge portions being inclined relative to said pad support and extending over substantially the entire width of the latter, a stack or pad of individual, ununitized, uniformly sized sheets arranged upon said pad support; one of the edges of said pad abutting with the inclined edge portion of said pad support, thereby causing the formation 65 of an incline at the edge of the pad disposed opposite to the abutting edge, said upturned

edge portions which are not inclined relative to said pad support provided with weight guides, a weight bar in engagement with said guides adapted for a downward movement and further adapted to rest upon and compress said sheet pad, allowing the removal of the topmost sheets without disturbing the sheets of the rest of the pad.

70 3. A sheet pad holder, comprising a pad support having a plurality of upturned edges 75 forming upright and inclined pad-limiting means, the inclined limiting means serving as abutment for a stock of individual, unattached sheets, said upright means provided with weight guides, a weight bar, capable of 80 a downward movement, disposed between and having portions slideable in said guides and adapted to compress a stock or pad of sheets resting upon said pad support, allowing the removal of the uppermost sheets 85 without disturbing the remaining sheets.

90 In testimony whereof I affix my signature.

GENNARO DE PAMPHILIS.
